UNITED STATES PATENT OFFICE.

FRANCIS BURESH, OF MAPLELEAF, IOWA.

ADDING-MACHINE.

SPECIFICATION forming part of Letters Patent No. 748,924, dated January 5, 1904.

Application filed March 16, 1903. Serial No. 147,988. (No model.)

To all whom it may concern:

Be it known that I, FRANCIS BURESH, a citizen of the United States, and a resident of Mapleleaf, in the county of Howard and State 5 of Iowa, have invented a new and Improved Adding-Machine, of which the following is a full, clear, and exact description.

The purpose of my invention is to provide a reliable adding-machine of exceedingly simple construction and which may be conveniently and expeditiously operated and applied directly to the columns of figures to be added, and, further, to provide the machine with an indicator which as the machine is moved 15 down a column of figures to be added will be at the right or at the left, as desired, or which may be made to cover or conceal the last figure added.

Another purpose of the invention is to provide a machine of the character described which will be light, small, and may be readily used in account-books or on individual sheets of figures and which when in position will indicate the column being added, as well as 25 the next figure to be added in the column and which may be readily moved from one column to the other.

A further purpose of the invention is to provide means for operating the machine by 30 a single lever having movement with reference to a scale of figures independent of the total-adding mechanism.

The invention consists in the novel construction and combination of the several 35 parts, as will be hereinafter fully set forth, and pointed out in the claims.

Reference is to be had to the accompanying drawings, forming a part of this specification, in which similar characters of reference indicate 40 corresponding parts in all the figures.

Figure 1 is a plan view of the adding-machine, illustrating its application to a sheet containing columns of figures to be added, three of the columns having been added, the 45 machine being shown in position to commence the addition of the fourth or final column. Fig. 2 is a transverse section taken practically on the line 2 2 of Fig. 1, and Fig. 3 is a longitudinal section taken practically on the line 50 3 3 of Fig. 1.

A represents a base, which is made as light as possible consistent with strength, and said

base may be made of wood, aluminium, or other equivalent material. In the upper face of the said base a depression 10 is produced, 55 as is shown best in Fig. 1, and on this depressed surface 10 a scale A' appears, the division-lines 11 of which extend transversely across the said depressed surface, as is also shown in Fig. 1. These lines commence at a point 60 near the right-hand end of the depressed surface 10 and extend to the left-hand end of said surface, and adjacent to each line a number is produced, which numbers read from "1" to "9," the number "1" appearing at 65 the initial or right-hand division-line 11 of the scale, and about centrally between the ends of the said scaled surface of the body A an indicating-finger 12 extends from the lower edge of the said body, and this indicating- 70 finger in the use of the machine may be brought over a figure in the column which has just been added or opposite a figure to be added, either to the right or to the left of such figure.

In connection with the body A an adding-wheel B is employed, mounted to revolve upon what may be termed the "upper" portion of the body at its outer face or upper face. This adding-wheel B is provided upon 80 its outer face with a circularly-arranged scale B', the divisions of which are numbered consecutively from "1" to "100," and at each division of the scale B' on the adding-wheel B a tooth 13 is peripherally formed. 85 All these teeth incline in the same direction.

The adding-wheel B is prevented from moving backward or is compelled to move in one direction only through the medium of a pawl 14, which engages with a tooth 13 on 90 the adding-wheel, and this pawl, which is preferably made of spring material or may be controlled by a spring, is secured at one end in a bearing 15, adjustably mounted, preferably, near the right-hand side of the 95 body A at a point below the said adding-wheel B, as is shown in Fig. 1.

The adding-wheel B is not shown mounted to turn directly on the upper face of the body A, but upon the upper face of a block or extension 16 from the said body, which is secured in any approved manner to the upper face of the body, and this block or extension 16 from the body A is made more or less cir-

cular, so that it will not extend beyond the toothed peripheral portion of the said adding-wheel B. In the under face of the extension 16 of the body a recess 17 is produced, (shown in Fig. 2,) and this recess extends from the central portion of the said extension 16 of the body to and through the lower edge of the said extension, the said recess 17 being more or less V-shaped and widest at its lower or outer end. The adding-wheel B is pivoted on the extension 16 of the body A by means of a suitable pivot-pin 18, which may be carried through the body, if desired, or may be secured in the body at its lower end in any desired manner. This pivot-pin 18 is likewise passed through an opening at the upper end of the operating-lever C, the upper portion of which lever extends in the said recess 17 and has movement therein. Therefore the upper end of the operating-lever C is pivoted centrally with respect to the adding-wheel B; but the operating-lever C is independent of the said adding-wheel. This operating-lever C extends over the scale-surface A' of the body A, as is also shown in Fig. 1, and preferably at the lower end of the said operating-lever C a handle C' is pivoted, enabling the operator to move the operating-lever C over the scale A' in a most convenient manner. The operating-lever C is guided in its movement by being passed beneath a guide-yoke 19, which is secured to the body A of the machine above the depressed scale-surface A' of the body. This operating-lever C is provided with a pointer 20 at its left-hand edge, where it moves over the said scale A' of the body, the outer edge of which pointer is straight, and in the operation of the machine the outer straight edge of this pointer 20 is brought in parallelism and is made to register with a division-line 11 of the scale A' on the body, adjacent to which the figure appears which is to be added to a total by the operation of the adding-wheel B.

The adding-wheel B is given movement through the medium of a spring-dog 21, which dog is normally in engagement with one or the other of the peripheral teeth 13 on the adding-wheel, and preferably one end of the said spring-dog 21 is secured to the operating-lever C. As illustrated, this attachment is made by producing an upwardly-extending loop 22 in the said operating-lever C, through which the heel end of the dog 21 is passed and secured, as is illustrated in Fig. 3. The adding-wheel B is turned by the operator, when so desired, through the medium of a knob 23, which extends from the upper face of the said adding-wheel, as is shown in Figs. 1 and 2.

At the right-hand side of the body A a shield 24 is secured, which, as is shown in Figs. 1 and 2, extends upward at the right-hand edge of the said body and then across the scale-section B' of the adding-wheel B at the right-hand central portion of the said

wheel, as is particularly shown in Fig. 1. The outer member of this shield may be termed a "pointer" member, and its lower edge is straight, so that it may be brought in registry with any division-line in the scale B' of the adding-wheel B, while its opposing edge is more or less inclined or beveled, so that a portion of the figure over which the pointer member of the shield extends is visible, enabling the said figure to be easily read.

An extension 25 is made from the left-hand side edge of the body, preferably opposite the shield 24, and on this extension 25 from the body the inner end of the handle 26 is secured by means of a thumb-nut 27 or equivalent means.

In the operation of this machine the adding-wheel B is turned by hand until the number "100" is below the pointer member of the shield 24. The adding-wheel being in this position, the machine is placed upon the book or sheet containing the columns of figures to be added, being so placed initially that the indicating-finger 12 at the bottom of the body will be either above the first figure in the units-column or at the right or the left hand side of such figure, and, further, before or after the machine has been thus placed in position the operating-lever C is carried to the right until its left-hand edge will be to the right of the initial division-line 11 of the scale A', which line is numbered "1." In adding a column of figures, as per the example shown in the drawings, the operating-lever C is first moved so that the left-hand edge of its pointer 20 will be brought in registry with the division-line marked "2" on the scale A', as the first figure in the said units-column is the figure "2." The operating-lever is then moved to the right, preferably to an engagement with the right-hand end of the depression 10 on which the scale A' is produced, and under this movement of the operating-lever C the dog 21 will have moved the adding-wheel B a distance of two of its teeth 13, thus bringing the figure "2" beneath the pointer member of the shield 24.

As the next figure in the units-column is also "2," the operating-lever C is carried to the division-line indicated by the figure "2" again, and is then carried once more to the right-hand end of the depression 10, thus causing the dog 21 to again move the adding-wheel B the distance of two teeth and bringing the figure "4" on the scale B' of said wheel beneath the pointer member of the shield 24. The next figure in the units-column to be added is "3." The operating-lever C is then carried across the scale A' until the left-hand edge of the pointer 20 is brought in registry with the division-line marked "3" on the scale A', and is then carried to the right-hand end of the depressed surface 10, upon which said scale is produced, thereby causing the adding-wheel B to be moved the distance of three teeth, bringing the figure "7" below the pointer member of the shield 24. The last figure shown in the

units-column of the example is "6." Therefore the operating-lever C is again moved over the scale A' until the left-hand edge of its pointer 20 is in registry with the division 5 line 11 on the scale A', designated as "6," whereupon the operating-lever is carried again to the right-hand end of the depressed section 10, on which the scale A' is produced, thereby causing the dog 21 to revolve the adding-wheel B the distance of six teeth, causing the figure "13" to be brought beneath the indicating member of the said shield 24. This figure "13" will designate the total of the addition of the figures in the units-column. The 10 figure "3" of the total "13" is then placed below the units-column on the second line to designate the unit of the total, and the figure "1" is placed beneath the lowest figure in the tens-column. The operator will now reverse 15 the adding-wheel B to bring it again in such position that the number "100" will be beneath the indicating member of the shield 24, and the machine is then shifted in a manner 20 to bring the indicating-finger 12 at the bottom of the body over the upper portion of the tens-column or the next column to be added, or to the right or to the left of the first figure in such column, and this column is then added 25 in the same manner as has been described with reference to the units-column. Thus each 30 column of figures is added, and as the total of each column is obtained upon the adding-wheel B the right-hand figure of said total is set down beneath the column added, while the left-hand figure of the total, or the figure to be 35 carried, is set down beneath the last figure of the next column to be added, and as the total of each column is obtained and the results set down, as stated, the adding-wheel B is 40 turned to bring the numeral "100" beneath the pointer member of the shield 24.

When the machine is operated, it is held by the left hand by means of the handle 26, and the operating-lever is manipulated by the 45 right hand.

Having thus described my invention, I claim as new and desire to secure by Letters Patent—

1. In an adding-machine, a support, an adding-wheel mounted to revolve upon the upper face of the support and provided with a scale in figures, the said support having a depression in its upper face, a scale upon the depressed surface of the support likewise in 55 figures, and an operating-lever having movement relative to the scale upon the depressed portion of the support and an operating connection between the operating-lever and the adding-wheel, substantially as described.

2. In an adding-machine, a support comprising a base and an extension on the upper face of the base having a recess in its under face, an adding-wheel mounted to revolve upon the upper face of the said extension and 65 provided with a scale in figures, a scale upon the base likewise in figures, an operating-lever extending in the said recess in the under

face of the extension and having movement relative to the scale upon the base, and a driving connection between the operating-lever and the adding-wheel, operating only when the lever is moved in one direction to move the adding-wheel a corresponding number of points to the point or points indicated upon the base-scale at which the lever may 75 be stopped, as described.

3. In an adding-machine, a body-section, an adding-wheel mounted to revolve upon the body-section, having a circularly-arranged scale in figures reading from 1 to 100, a scale 80 upon the face of the body-section below the adding-wheel and reading from 1 to 9, an operating-lever pivoted at the central portion of the adding-wheel and provided with a pointer adapted to register with any division 85 of the scale on the body, a guide-yoke on the face of the body-section above the said scale and beneath which the lever passes, a dog carried by the operating-lever in operative engagement with the adding-wheel, and a de- 90 tent for the adding-wheel, as described.

4. In an adding-machine, a body-section, an adding-wheel mounted to revolve upon the body-section, having a circularly-arranged scale in figures reading from 1 to 100, a scale 95 upon the body-section reading from 1 to 9, an operating-lever pivoted at the central portion of the adding-wheel and provided with a pointer adapted to register with any division 100 of the scale on the body-section, a dog carried by the operating-lever in operative engagement with the adding-wheel, a detent for the adding-wheel, an indicating-finger extending from the scale-surface of the body-section, and a pointer carried by the body 105 over the adding-wheel, adapted to cover a figure of the scale of said wheel, substantially as described.

5. In an adding-machine, a body-section, an adding-wheel mounted to revolve upon the 110 body-section, provided with a circularly-arranged scale in figures and a peripheral tooth for each division of the scale, a scale in figures produced upon the body-section, an operating-lever fulcrumed at the pivot-point of 115 the adding-wheel and extending over the body-scale, adapted to register with any division of the body-scale, a dog carried by the operating-lever, engaging with the teeth of the adding-wheel, a pointer for the adding-wheel, a detent operating on the teeth of the adding-wheel, an indicating-finger extending from the body-scale, and a handle for the body-section, substantially as described.

6. In an adding-machine, an adding-wheel 125 having a scale in figures, a support for the wheel, a scale in figures upon the support, an operating-lever extending over the scale of the support, adapted to act in conjunction with said scale, and an indicating-finger ex- 130 tending beyond the support from the scale thereon, as described.

7. In an adding-machine, a support, an adding-wheel mounted to revolve upon the up-

per or outer face of the support and provided with a scale in figures, a pointer for the adding-wheel carried by the support, a scale upon the face of the support at one end thereof, 5 likewise in figures, an indicating-finger extending from the edge of the support, an operating-lever having movement relative to the scale upon the face of the support, and an operative connection between the operating-le-

ver and the adding-wheel, substantially as 10 described.

In testimony whereof I have signed my name to this specification in the presence of two subscribing witnesses.
